UNITED STATES PATENT OFFICE.

ARTHUR L. VAN VEEN, OF NEW YORK, N. Y.

DESIGN FOR A BRACKET.

57,287.

Specification for Design.

Patented Mar. 8, 1921.

Application filed December 11, 1920. Serial No. 430,065. Term of patent 7 years.

To all whom it may concern:

Be it known that I, ARTHUR L. VAN VEEN, a citizen of the United States, residing at New York city, in the county of New York and State of New York, have invented a new, original, and ornamental Design for Brackets, of which the following is a specification, reference being had to the accompanying drawing, forming part thereof.

Figure 1 is a front elevational view of a bracket showing my new design;

Fig. 2 is an end elevational view thereof; and

Fig. 3 shows the bracket in use in connection with the cornice or top molding of cabinet construction and illustrates one of the possible uses of my new bracket design.

I claim:

The ornamental design for a bracket as shown and described.

ARTHUR L. VAN VEEN.
